[57] CLAIM

The ornamental design for a water slide, as shown and described.

DESCRIPTION

FIG. 1 is a top, front and left side perspective view of a water slide showing our new design;

FIG. 2 is a fragmentary perspective of the slide platform;

FIG. 3 is a sectional view taken on the line 3—3 of FIG. 1;

FIG. 4 is a top plan view;

FIG. 5 is a bottom plan view;

FIG. 6 is an elevation of the rear end; and

FIG. 7 is a fragmentary perspective of the water slide end portion.

The side elevation view is the same for both sides.
